(57) **CLAIM**

The ornamental design for an access floor panel, as shown and described.

DESCRIPTION

FIG. 1 is a front view of an access floor panel of our design, the rear view being a mirror image of the front view;

FIG. 2 is a top view thereof;

FIG. 3 is a right-side view thereof, the left-side view being a mirror image of the right-side view;

FIG. 4 is a bottom view thereof, the lower right corner is enclosed in broken lines to indicate that this portion is illustrated in FIG. 8.

FIG. 5 is an enlarged partial cross-sectional view taken along lines 5-5 in FIG. 2;

FIG. 6 is an enlarged partial cross-sectional view taken along lines 6-6 in FIG. 2;

FIG. 7 is a cross-sectional view thereof taken along lines 7-7 in FIG. 4; and,

FIG. 8 is an enlarged partial perspective view thereof of the portion indicated in FIG. 4.
